UNITED STATES PATENT OFFICE.

CHARLES E. HAGUE, OF ROCHESTER, NEW YORK, ASSIGNOR, BY MESNE ASSIGNMENTS, TO WESTERN ELECTRIC COMPANY, OF CHICAGO, ILLINOIS, A CORPORATION OF ILLINOIS.

TELEPHONE SYSTEM.

1,128,777.

Specification of Letters Patent. Patented Feb. 16, 1915.

Application filed April 22, 1910. Serial No. 556,924.

To all whom it may concern:

Be it known that I, CHARLES E. HAGUE, a citizen of the United States, residing in Rochester, county of Monroe, and State of New York, have invented certain new and useful Improvements in Telephone Systems, of which the following is a specification.

My invention relates to telephone systems and more particularly to telephone systems of the class known as call-distributing systems. In systems of this character means is provided whereby an incoming call may be handled manually by the first operator in the exchange who is not busy attending to another call. In this manner the number of required operators is reduced, since the calls may be so distributed that each operator is kept working to her maximum efficiency at all times.

My invention relates to trouble indicating features of the line switch circuit, to the intermediate switch circuit, and also to the cord circuit arrangement for use with this system and to the means provided therein whereby only two calls may be received by a single operator simultaneously.

The system here illustrated is such a system as would be used in a large telephone exchange wherein it is desirable to interconnect a number of telephone lines exceeding twenty-five hundred. In general therefore I provide a line switch for each line-capable of selecting any one of a number of intermediate switches, these intermediate switches being capable of selecting any one of a large number of cord circuits.

My invention further consists in the improvements in electrical connections and apparatus whereby an economic and efficient combination resulting in an operative common battery telephone call-distributing system is produced, and in the further details and combinations described in the specification and specifically claimed.

My invention is illustrated in the accompanying drawing consisting of a single system distributed for convenience upon three sheets.

Figure 1 is an illustration of the calling telephone line and the line selector switch, Fig. 2 is an illustration of the intermediate

selector switch and Fig. 3 is an illustration of the cord or connecting circuit and the telephone line to be called.

55

My invention, as here illustrated, is shown applied to a two wire common battery system, by which is meant that the system operates with only two wires between the exchange and the subscriber's instrument, a third wire or ground being unnecessary between the subscriber's instrument and the central office, and that a single source of direct current located at the central office suffices for supplying energy for both signaling and talking purposes.

Referring to Fig. 1, the calling subscriber's station 1 is provided with the usual annunciator 2 and condenser 3 connected in a bridge between the limbs 4 and 5 of the telephone line, and with the transmitter 6 and receiver 7 adapted to be placed in a bridge between the limbs of the line by the actuation of the switch-hook 8. At the central office line conductor 4 extends through the normal contacts 9 and 10 of cut-off relay 11 and through the coil 12 of line relay 13 to the battery wire 14 which is shown connected with the live pole of battery A illustrated on Fig. 3. The line conductor 5 extends, at the central office, through normal contacts 15 and 16 of cut-off relay 11 and thence through the coil 17 of relay 18 to the ground pole of battery A. Cut-off relay 11 is also provided with normally open contacts 20 and 21 adapted, when the relay is actuated, to extend the limbs 4 and 5 of the line to the lever contacts 22 and 23 of relay 18, the lever 22 of relay 18 being connected through the normal contact 24 and conductor 25 through the coil 48 of cut-off relay 11 to ground. Relay 11 also has the coil 27, one terminal of which is connected with the live pole of battery A and the other terminal of which is connected through conductor 26

80

and the coil 28 of relay 18 and conductor 29 with the contact 30 of cut-off relay 11. This contact 30 is adapted when actuated to connect with contact 31 which extends to the lever 32 of relay 18 and thence through the normal contact 33 to the lever 34 of line relay 13, this lever being normally connected through its contact 35 with conductor 26. Contact 37 of the set of contacts of cut-off

85

and conductor 25 through the coil 48 of cut-off relay 11 to ground. Relay 11 also has the coil 27, one terminal of which is connected with the live pole of battery A and the other terminal of which is connected through conductor 26 and the coil 28 of relay 18 and conductor 29 with the contact 30 of cut-off relay 11. This contact 30 is adapted when actuated to connect with contact 31 which extends to the lever 32 of relay 18 and thence through the normal contact 33 to the lever 34 of line relay 13, this lever being normally connected through its contact 35 with conductor 26. Contact 37 of the set of contacts of cut-off

90

95

100

relay illustrated as "make before break" contacts extends to normally open contact 38 of line relay 13, the lever 39 of that relay being connected through conductor 40 and the coil of the line switch motor-magnet 41 through the interrupter 42 to the battery wire 14. The contact lever 32 of relay 18 also connects with the contact 44 of relay 13, the normally open contact 45 of that relay being connected through the winding 46 of said relay, conductor 47 and the coil 48 of relay 11 with earth. Line relay 13 also has the normally open contact 65 adapted to connect the lever 34 with earth when the relay is actuated.

15 The multiple jacks 50 have their sleeve contacts 51 connected to the inside contact 20 of cut-off relay 11 and their tip contacts 52 connected to the inside contact 21 of cut-off relay 11.

20 Relay 18 has the normally open contacts 53 and 54 adapted, when the relay 18 is actuated, to extend the line conductors 4 and 5 through conductors 55 and 56 to the collector segments 57 and 58 of the line switch 60. Relay 18 also has the normally open contact 61 adapted, upon the actuation of the relay, to connect the lever 32 through conductor 63 with the third or private collector segment 64 of the line switch 60.

25 Line switch 60, which is here shown only conventionally comprises the circle of insulated contacts held between insulating rings 67 by the clamping screws 68, and the three segments 57, 58 and 64 electrically separated and mounted so that the brushes 69, 70 and 71 will close the electric circuits between these segments and three contacts in the circle for each of the various rotary 30 positions of the brush spider. A further description of this switch will appear later in the specification.

35 In the illustrated position the talking strand 55 is shown connected by brush 69 through segment 57 and contact 73 with conductor 74. Talking conductor 56 is shown connected by means of the brush 70 through segment 58 and contact 75 to conductor 76, and conductor 63 is shown connected by means of brush 71 through segment 64 and contact 77 to conductor 78, this latter conductor being known as the private conductor as distinguished from the talking circuit. Conductors 74, 76 and 78 40 continue to Fig. 2 where they bear the same numerals.

45 In Fig. 2 conductor 74 is normally connected through contacts 80 and 81 of cut-off relay 82 and the coil of relay 83 to the battery conductor 14, and conductor 76 is normally connected through contacts 84 and 85 of cut-off relay 82 to earth. The relay 83 is provided with normally open contacts 86 and 87, contact 86 extending through conductor 88 and the coil of the vertical motor-

50 magnet 89 and interrupter 90 to the battery conductor 14, and the contact 87 extending through conductors 91 and 92, the normally closed rotary off-normal contacts 93 and 94, conductor 95, the vertical wiper 96 and the lower vertical contact 97 to earth. The relay 83 is also provided with the lever contact 98, normal contact 99 and open contact 100, the lever 98 being connected through conductor 101 with the rotary private wiper 102, which in turn connects during the actuated condition of the intermediate switch with rotary contact 103 and private conductor 104. The normally closed contact 99 connects through conductor 105 and the coil 106 of relay 82 with the normally open inside contact 107 of that relay. The normally open contact 100 of relay 83 is connected through conductor 108 with the normally open contact 109 of relay 110, the lever contact 111 of relay 110 being connected through the coil of the rotary motor-magnet 112 and the interrupter 90 with the battery wire 14. The lever contact 115 of relay 82 is connected through conductor 116 and the coil of release magnet 117 with the battery wire 14. The contact 118 of relay 82 which is normally touching lever 115 is connected through the normal contacts 119 and 120 of relay 83 and conductor 121 to the normally open contact 122 of the vertical off-normal springs, this same spring being also connected through the coil 123 of relay 82 with the normally open contact 124 of relay 110, the other open contact 125 of this relay being joined with contact 111. Contact 122 of the vertical off-normal springs is also connected through conductor 127, contacts 128 and 129 of the rotary off-normal springs and conductor 130 to the lever contact 98 of relay 83. One of the vertical off-normal contacts 132 is connected with earth and the third contact 133 is connected with the private conductor 78, these three contacts being normally separated and being bunched when the switch is in its actuated condition. The normally open contacts 134 and 135 of cut-off relay 82 are adapted to extend the talking conductors 74 and 76 through conductors 136 and 137 to the wipers 138 and 139, these wipers being connected during conversation through contacts 140 and 141 with the talking conductors 142 and 143 which extend to talking conductors bearing the same numerals 140 on Fig. 3 of the drawing.

100 In Fig. 3 the talking conductors 142 and 143 are shown extending through condensers 144 and 145 and contacts 146 and 147 and 148 and 149 of the operator's listening and ringing keys to the sleeve 150 and tip 151 respectively of the calling plug. The relays 153 and 154 have their coils connected in a bridge between the talking conductors 143 and 142, this bridge containing 130

the main battery A. Relays 164 and 165 likewise have their coils connected in a similar bridge of the talking circuit on the calling side of condensers 144 and 145. Relay 153 has the normally open contacts 155 and 156, the contact 155 being connected with earth and the contact 156 being connected with the normally closed contact 157 which connects with the lever contact 158, said contact being connected through the normal contacts 159 of the busy key 160 with the private conductor 104. This key also has the normally open contact 161 which is connected to earth and is adapted upon the actuation of the key to ground the private conductor 104. The normally open ground contact 162 of relay 153 is adapted to connect with the lever 158 of that relay when the relay is actuated. Relay 154 has a lever contact 166 connected through conductor 167 with one terminal of the call lamp 168, the other terminal of this lamp being connected with the live pole of battery A. The lever 166 of relay 154 is normally connected with contact 169 and thence through conductor 170 to the normally open contact 171 of relay 165 and also through the normally closed contacts 172 and 173 of relay 164 to one terminal of the calling supervisory lamp 174, the other terminal of this lamp being connected with the live pole of battery A. The relay 154 has the normally open contact 175 which is connected through conductor 176 with the normally closed contact 177 of relay 165, the lever 178 of relay 165 being connected with earth. The contact 157 of relay 153 is also connected through conductor 180 with the lever contact 181 of relay 165, this contact being normally connected through contact 182 with the conductor 183 which conductor is connected by means of the branch wires 184 to similar contacts 182, associated with one half of the other cord circuits appearing in the same operator's position as the cord circuit here illustrated, and it is to be understood that these other cord circuits are theoretically represented by the branch wires 184 to such an extent that they may be claimed in the appended claims of this specification. Contact 181 of relay 165 is adapted to connect with contact 185 when the relay is actuated, the latter contact being connected with earth.

55 The operator's listening key 190 has the contacts 191 and 192 normally completing the tip strand of the talking circuit and has the contacts 193, and 194 and 195 adapted when the key is actuated to place the operator's receiver 196, secondary 197 of induction coil 198 and condenser 199 in a bridge between the talking conductors. The operator's listening key 190 also has the auxiliary contacts 200 and 201 adapted upon the actuation of the key to connect the tip of the

calling plug through the tertiary winding 203 of the operator's induction coil 198 to earth. The primary winding 204 of this induction coil is connected in series with the operator's transmitter 205 and any suitable source of current not shown in the drawing. The relay 165 has the normally open contacts 207 and 208 adapted when actuated to close a shunt about contacts 191 and 192 of the operator's listening key 190.

5 The operator's ringing key 210 has the normally open contacts 211 and 212, the contact 211 being connected through the ringing generator 213 to earth and the contact 212 being connected through the non-inductive resistance 214 to battery conductor 14.

The called telephone line 1' illustrated at the right of Fig. 3 is equipped with apparatus identical with the apparatus illustrated and described in connection with the calling telephone line 1, the corresponding apparatus of the called telephone line being designated by like figures with the suffix ('), it being understood that the complete apparatus of the called telephone line, part of which is omitted from this drawing for the sake of clearness, is so theoretically illustrated that it may be claimed in the pending claims.

95 The conventional drawing of the intermediate switch shown on Fig. 2 is intended to illustrate any form of connecting apparatus to which the other features of my invention may be applied. This switch comprises the vertical shaft 220 carrying the private and talking wipers 102, 138 and 139 in insulated relation to the shaft and to one another, but so secured to the shaft that they move therewith as a unit. Also secured to this shaft is the vertical cylindrical ratchet by means of which the vertical motor-magnet 89 is adapted to step the shaft 220 and all parts integral therewith vertically. This ratchet cylinder is also engaged by the 100 prong 221 of double-dog 222 which dog is adapted to be attracted by the release magnet 117 for permitting the shaft 220 to return to its normal position. Upon the upper end of this shaft the ratchet wheel 223 is mounted and is so keyed to the shaft that the shaft can slide up and down through the ratchet wheel, but that the shaft and ratchet wheel are caused to rotate as a unit. This ratchet wheel is adapted to be engaged by the pawl 224 which is adapted to be actuated by the rotary motor-magnet 112, this pawl as well as the pawl of the vertical magnet being normally held out of engagement with the ratchet teeth by means of 105 pins 225 and 226. Upon the upper face of the ratchet wheel 223 an insulating button 227 is secured which is adapted, when the ratchet wheel is in normal position, to so engage the rotary off-normal spring 94 as to 110

115

120

125

130

raise this spring and maintain the contacts 93 and 94 and contacts 128 and 129 in closed condition.

On the lower end of the shaft 220 the insulating collar 230 is so mounted that the shaft may readily rotate therein, but that the collar is caused to move up and down with the shaft as a unit. This collar carries the vertical wiper 96 which is double the same as 10 private wiper 102, the other half, not shown because it is concealed by the part here illustrated, rubbing lightly against the back of the bank of vertical contacts 231, these two brushes and their contact with the bank 231 15 acting as a guide to prevent the collar 230 rotating with the shaft.

The lower contact 97 of the set 231 is connected to ground, the second contact of the group is connected to the armature of relay 20 235, the third to the armature of relay 236, the fourth to the armature of relay 237 and the fifth to the armature of relay 238, the coil of this latter relay being connected through conductor 239 with the lever contact 240 of relay 154 in Fig. 3. Conductor 239 is also connected to similar contacts 240 in relays 154 of nine other cord circuits. Contact 240 of relay 154 is normally connected through conductor 241 and the contacts 242 of the operator's busy key 160 with earth, and upon the actuation of relay 154 contact 240 is adapted to connect through contact 243 and non-inductive resistance 244 with battery conductor 14. The upper terminal 25 of the non-inductive resistance 244 is connected with the contacts 243 of the nine other cord circuits to which conductor 239 is connected. This particular group of ten cord circuits are connected to the various contacts 240 of the intermediate selector switch which comprise the fourth row of contacts.

In the operation of my system the subscriber in charge of substation 1 removes the receiver 7 from the switch-hook 8 and thereby closes an electric circuit from the live pole of battery A through conductor 14, the coil 12 of relay 13, contacts 10 and 9 of relay 11, line conductor 4, transmitter 6, receiver 7, switch-hook 8, line conductor 5, contacts 15 and 16 of cut-off relay 11 and the coil 17 of relay 18 to earth. The current in this path actuates relays 13 and 18 completing the circuit from the battery A through conductor 14, interrupter 42, motor-magnet 41, conductor 40, contacts 39 and 38 of relay 13, contacts 37 and 31 of relay 11, contacts 32 and 61 of relay 18, conductor 63, contact segment 64, brush 71 and the various busy or grounded contacts of the line switch. The interrupter current in this path steps the line switch from one position to another until the private brush 71 arrives at a contact such as 77 which is not grounded. Instantly the current through the in-

terrupter 42 and the motor-magnet 41 takes a new path over conductor 40, contacts 39 and 38 of relay 13, contacts 37 and 31 of cut-off relay 11, contacts 44 and 45 and coil 46 of relay 13, conductor 47 and the coil 48 of cut-off relay 11 to ground. The current in this path is not sufficient to actuate motor-magnet 41 but actuates the cut-off relay 11 and immediately closes a locking circuit for relays 11, 18 and 13, this circuit extending from the battery conductor 14 through the coil 27 of relay 11, conductor 26, coil 28 of relay 18, conductor 29, contacts 30 and 31 of the now actuated cut-off relay 11, contacts 44 and 45 and coil 46 of relay 13, conductor 47 and the coil 48 of relay 11. In this manner the three relays associated with the line are held in their actuated positions and line conductor 4 is extended through contacts 9 and 20 of the cut-off relay 11, contacts 22 and 53 of relay 18, conductor 55, segment 57, brush 69 and contact 73 to the talking conductor 74 which extends to Fig. 2. Likewise line conductor 5 is extended through contacts 15 and 21 of cut-off relay 11, contacts 23 and 54 of relay 18, conductor 56, segment 58, brush 70 and contact 75 to the talking conductor 76 which extends to Fig. 2. If the line switch had been normally standing on idle contacts the cut-off relay would have been actuated over this same path without the line switch moving from its initial position.

Referring now to Fig. 2, the line circuit of Fig. 1 being still closed at the substation a circuit is completed from the live pole of battery through conductor 14, the coil of relay 83, normal contacts 81 and 80 of relay 82, talking conductor 74 and the path formerly traced through the line circuit apparatus and the substation back to conductor 76, thence through contacts 84 and 85 of relay 82 to ground. The current in this path actuates relay 83, changing its contacts to their abnormal position and immediately completing a circuit from the battery conductor 14 through interrupter 90, the coil of the vertical motor-magnet 89, conductor 88, contacts 86 and 87 of relay 83, conductor 91, conductor 92, the now closed contacts 93 and 94 of the rotary off-normal springs, conductor 95, the vertical wiper 96 and grounded contact 97 of the vertical bank 231. The current in this path actuates the motor-magnet 89 stepping the shaft 220 up one step and thereby closing the contacts 122, 133 and 132 of the vertical off-normal set of springs. The closing of this latter set of contact springs connects the ground pole of battery through contacts 132 and 133 and conductor 78, contact 77 (in Fig. 1), wiper 71, segment 64, conductor 63 and contacts 61 and 32 of relay 18, thus closing a shunt circuit about the coil 46 and the coil 48 of relays 13 and 11. This allows

relay 13 to become deenergized, but the relays 11 and 18 now remain energized by current from battery through their coils 27 and 28, conductor 29, contacts 30 and 31 of relay 11, contacts 32 and 61 of relay 18 to earth as formerly described through the contacts 133 and 132 of the vertical off-normal set of springs in Fig. 2. The relays 235, 236 and 237 being shown in their actuated positions, the three succeeding contacts above the grounded contact 97 in the vertical bank 231 are also grounded and therefore the vertical motor-magnet 89 will continue to receive impulses through the interrupter 90 until the shaft 220 has been stepped up sufficiently that the vertical wiper 96 steps off of the last grounded contact which extends to relay 237 onto the ungrounded contact which extends to relay 238. When this occurs the current through the interrupter 90 will follow a new path extending through the coil of motor-magnet 89, conductor 88, contacts 86 and 87 of relay 83 and the coil of relay 110 to ground. This relay is of high resistance compared with the resistance of the motor-magnet 89 so that the relay will be actuated but the motor-magnet will not operate to raise the shaft 220.

Upon the actuation of relay 110 a path for current is established from the live pole of battery A through interrupter 90, the coil of the rotary motor-magnet 112, contacts 111 and 109 of the relay 110, conductor 108, contacts 100 and 98 of relay 83, conductor 130, contacts 129 and 128 of the rotary off-normal set of spring, conductor 127, conductor 121 and the contacts 122 and 132 of the vertical off-normal set of springs to ground. The current in this path actuates the rotary motor-magnet 112 and moves the shaft 220 through one rotary step. This moves the insulating button 227 out from under the rotary off-normal set of springs changing the circuit of said springs to the condition shown in the drawing and therefore interrupting the circuit through the motor-magnet 112 at the now interrupted contacts 128 and 129 of the rotary off-normal set of springs.

The first rotary step of the shaft 220 brings the private wipers 102 into contact with the first rotary set of private contacts 103, this set of contacts extending to the cord circuit which, as will be later shown, if busy, maintains a ground on its private wire, which extends to the various contacts 103. Therefore assuming the first few contacts 103 to have been busy and therefore grounded, current will flow from the live pole of battery A through the interrupter 90, coil 112 of the rotary motor-magnet, contacts 111 and 109 of relay 110, conductor 108, contacts 100 and 98 of relay 83, conductor 101, wiper 102, the busy contacts 103

to ground. The shaft 220 will therefore be moved step by step in a rotary direction until wipers 102 step off the last busy contact 103 onto an idle and therefore not grounded contact. When this occurs a new path for current is taken through the interrupter 90, coil of rotary motor-magnet 112, contacts 125 and 124 of relay 110, coil 123 of relay 82, conductor 121 and contacts 122 and 132 of the vertical off-normal set of springs to ground. The coil 123 of relay 82 being of much higher resistance than the coil of motor-magnet 112, the relay 82 is actuated, but the shaft 220 is not given a further rotary step.

Upon the actuation of relay 82 the circuit of relay 83 is interrupted at contacts 80 and 81 of relay 82 and the circuit of relay 110 is in turn interrupted at contacts 86 and 87 of relay 83. A locking circuit is therefore immediately established through the coil 106 of relay 82, this circuit being traced as follows: from battery wire 14 and through the coil of release magnet 117 which magnet is of low resistance and is not actuated in series with the coil 106 of relay 82, conductor 116, contacts 115 and 107 and coil 106 of relay 82, the now closed contacts 99 and 98 of relay 83, conductor 101, private wiper 102, private contact 103, conductor 104, contacts 159 of key 160 (Fig. 3) and contacts 158 and 162 of relay 153 to earth, the relay being now actuated as will be explained later.

If, after the shaft 220 has commenced its rotary motion and the wipers 102, 138 and 139 have started across some particular row of contacts, all the contacts in this row become busy, then the shaft 220 will continue its rotary motion until the wipers 102 arrive at the last of the rotary contacts. This last contact is an extra or unused contact and therefore when the wipers 102 arrive at this position, relay 82 will be actuated as above described, but its locking circuit will not be closed through coil 106, since no ground will come upon the wipers 102. Relay 106 will therefore immediately fall back to its normal position whereupon the circuit of the release magnet 117 will be completed from the battery wire 14 through the coil of the magnet, conductor 116, contacts 115 and 118 of relay 82, contacts 119 and 120 of relay 83, conductor 121 and contacts 122 and 132 of the vertical off-normal set of springs to ground. This causes the shaft 220 and the wipers carried thereon to return to their normal position, or at least to return to the normal position so far as the rotary motion is concerned. The relay 83 will however be again actuated so that by the time the shaft has rotated back to its original position of rotation, the vertical magnet will again be actuated and will now step the switch up to the position op-

posite the next row of contacts and an idle trunk will then be selected in the next row. In this manner only a very slight delay is caused by the trunk becoming busy 5 after the switch has started on its rotary motion.

Returning to Fig. 2 the actuation of relay 82 extends the line circuit from conductor 74 through contacts 80 and 134, conductor 136, wiper 138, contact 140, conductor 142 and the coil of relay 154 (Fig. 3) to the live pole of battery A and extends conductor 76 through contacts 84 and 135 of relay 82, conductor 137, wiper 139, contact 141, conductor 143 and the coil of relay 153 (Fig. 3) to the ground pole of battery A. The current in this path actuated relays 153 and 154. The actuation of relay 153 connects the private conductor 104 with earth as has 10 previously been explained and also connects the earth side of battery through contacts 155 and 156, conductor 180 and contacts 181 and 182 through conductor 183 to the branch point 184 which is common to one half of 15 the cord circuits appearing at this particular operator's position. This, as will be seen, grounds one half of the private conductors 104 leading to this particular operator's position as long as sleeve relay 165 remains 20 unactuated. When this relay is actuated however the grounds are removed from all of the other cord circuits so that this operator may again receive calls. In this manner any particular operator may only receive 25 two calls simultaneously so that she will not be over-taxed.

The actuation of relay 154 closes its contacts 240 and 243, thus connecting battery from conductor 14 through the non-inductive resistance 244, contact 243 and 240 and conductor 239 to the coil of relay 238. The current however will not pass through the coil of relay 238 to ground until the relays 154 are actuated, which are associated with 30 all of the other nine cord circuits leading to the particular horizontal row of contacts in the intermediate switch to which the illustrated cord circuit leads. It will be seen that the common conductor 239 is normally grounded through contacts 240 and 241 of 10 relays 154, in ten different cord circuits and the contacts 242 of the keys 160. It will therefore require the actuation of all of these ten relays 154 to remove 35 this shunt about the coil of relay 238. Upon the removal of this shunt the current will pass through the coil of relay 238 and actuate that relay to ground another contact in the bank 231. The actuation of relay 154 40 also completes the circuit of the call lamp 168 from the live pole of battery A through the lamp, conductor 167, contacts 166 and 175 of relay 154, conductor 176 and contacts 177 and 178 of relay 165 to ground. The 45 display of the signal 168 indicates to the

operator that a calling subscriber has been automatically connected with this particular cord circuit with which the lamp 168 is associated and the operator therefore throws her listening key 190 and connects her receiver 196 in a bridge between the talking conductors of the cord circuit in a manner well known in the art. 70

Upon receiving the desired number the operator touches the tip 151 of the calling 75 cord to the sleeve contact 51' of the jack of the desired telephone line. If this line is busy either as a calling or as a called telephone line the sleeve of the jack will be maintained at a potential higher than that 80 of earth and a current will therefore flow from the sleeve of the tested jack through tip 151 of the calling plug, contacts 149 and 148 of the operator's ringing key 210, the now closed auxiliary contacts 201 and 200 85 of the operator's listening key 190 and the tertiary winding 203 of the operator's induction coil to ground. Current in this path will cause an inductive disturbance in the secondary 197 of the operator's induction 90 coil which will be heard in the operator's receiver 196. If however the desired line is found to be idle, the operator inserts her calling plug completely into the jack of the desired line, thus causing the tip and sleeve 95 contacts 151 and 150 of the plug to electrically register with the tip and sleeve contacts 52' and 51' of the jack. The operator now actuates her ringing key 210 which connects the live pole of battery A through conductor 14, non-inductive resistance 214, contacts 212 and 147 of the ringing key 210, sleeve contacts 150 and 51' of the plug and jack, contacts 22' and 24' of relay 18', conductor 25' and the coil 48' of cut-off relay 100 105 11' to ground. The current in this path actuates cut-off relay 11' moving its contacts 9' and 15' into their abnormal positions and connecting the tip and sleeve contacts 51' and 52' of the jack directly with the limbs 110 4' and 5' of the desired telephone line. At the same time the actuation of the ringing key 210 completes a circuit for the ringing generator 213 through contacts 211 and 149 115 of ringing key 210, the tip contacts 151 and 52' of the plug and jack, contacts 21' and 15' of cut-off relay 11', line conductor 5', annunciator 2', condenser 3', line conductor 4', contacts 9' and 20' of cut-off relay 11', sleeve contacts 51' and 150 of the jack and 120 plug, contacts 147 and 212 of ringing key 210 and the non-inductive resistance 214 to battery and back to the other pole of the ringing generator. The current in this path being alternating or pulsating passes 125 through the condenser 3' at the subscriber's station and sounds the annunciator 2', calling the subscriber to his telephone. The operator now releases her ringing key and thereupon completes a path for current from 130

the live pole of battery A through the coil of relay 165, contacts 146 and 147 of ringing key 210, sleeve contacts 150 and 51' of the plug and jack, contacts 22' and 24' of relay 18', conductor 25' and the coil 48' of cut-off relay 11' to ground, thus maintaining the actuation of cut-off relay 11' and actuating supervisory relay 165. The actuation of relay 165 severs its contacts 177 and 178 and 5 closes contacts 178 and 171. This severs the circuit of the call lamp 168 effacing that signal and completes a circuit for the calling supervisory signal 174 from the live pole of battery A through the signal, contacts 15 173 and 172 of relay 164 and the contacts 171 and 178 of relay 165 to ground. The actuation of relay 165 also severs contacts 181 and 182, thus removing the ground connection from conductor 183 and therefore 20 from the branch point 184 which frees the ground connection from one half the private wires extending to this particular operator's position. At the same time the contact 181 of relay 165 is grounded through 25 contact 185 of that relay so that the calling subscriber may now signal the operator without removing the ground connection from the private wire 104 which controls the release of the intermediate switch. The 30 actuation of relay 165 also closes contacts 208 and 207 which complete a shunt about contacts 191 and 192 of the operator's listening key 190.

When the called subscriber responds to 35 his call the removal of his receiver 7' from the switch-hook completes a path for direct current from the live pole of battery. A through the winding of relay 165, contacts 146 and 147 of ringing key 210, sleeve contacts 150 and 51' of the plug and jack, contacts 20' and 9' of cut-off relay 11', line conductor 4', transmitter 6', receiver 7', switch-hook 8', line conductor 5', contacts 15' and 21' of cut-off relay 11', tip contacts 52' and 40 151 of the jack and plug, contacts 149 and 148 of the ringing key 210, series contacts 192 and 191 of the operator's listening key 190 in parallel with contacts 207 and 208 of relay 165 and the coil of relay 164 to the 45 ground pole of battery A. The current in this path maintains the actuation of relay 165 and actuates relay 164, the actuation of relay 164 severing the circuit of the calling supervisory lamp 174 and indicating to the 50 operator that the called subscriber has answered his call. The calling and called parties are now in conversation and the apparatus heretofore described remains in the proper position to maintain an uninterrupted conversational circuit between the 55 two subscribers' stations so long as the telephone lines are maintained closed at the subscribers' stations. When the conversation has been terminated and the subscribers 60 return their receivers to their switch-hooks,

the two line circuits are thereby interrupted and the circuits of relays 153 and 154 and of relay 164 are interrupted, allowing these relays to return to their normal positions. This again displays the signal 174 through 70 the circuit formerly described and again displays signal 168 through the circuit completed from the live pole of battery A through the signal, conductor 167, contacts 166 and 169 of relay 154, conductor 176 and contacts 171 and 178 of relay 165 to ground. These signals now act as disconnect signals and indicate to the operator that both the calling and called subscribers have replaced their receivers upon their respective switch-hoops. 80

Upon receipt of the double disconnect signal the operator removes her calling plug from the jack with which it has been connected during conversation and thereby interrupts the circuit through the winding of relay 165 and the cut-off relay 11'. When the contact 181 of relay 165 moves away from its ground connection with contact 185, the circuit is interrupted from battery (Fig. 90 2) through the disconnect magnet 117, conductor 116, contacts 115 and 107 and coil 106 of relay 82, conductor 105, contacts 99 and 98 of relay 83, conductor 101, wiper 102, contact 103, private conductor 104, contacts 159 of the operator's busy key (Fig. 3), contacts 158 and 157 of relay 153, conductor 180 to the now open contacts 181 and 185 of relay 165. The severing of this circuit releases the relay 82 (Fig. 2) allowing that 100 relay to resume its normal position and close a low resistance path for battery from conductor 14 through the disconnect magnet 117, conductor 116, contacts 115 and 118 of relay 82, contacts 119 and 120 of relay 83, 105 conductor 121 and contacts 122 and 132 of the vertical off-normal set of springs to ground. The current in this path actuates the release magnet 117 returning the shaft 220 to its normal condition both as to its 110 rotary and vertical displacement. When this shaft returns to its normal position the vertical off-normal springs 122, 132 and 133 are mechanically opened by the weight of the shaft, thus severing the circuit through the release magnet, and allowing all of the apparatus associated with the intermediate switch to resume its normal and unactuated condition. The interruption of the circuit through the vertical off-normal springs 133 120 and 132 interrupts the circuit from the battery wire 14 (Fig. 1) through the coil 27 of cut-off relay 11, the coil 28 of relay 18, conductor 29, contacts 30 and 31 of cut-off relay 11, contacts 32 and 61 of relay 18, conductor 125 63, segment 64, brush 71, contact 77 and private conductor 78 which extends to the contact 133 of the vertical off-normal set of springs. The interruption of the circuit in this path releases the relays 11 and 18 al- 130

lowing them to return to their normal positions, the line switch 60 however remaining in the position in which it stood during conversation. The apparatus has thus all returned to its normal condition and may now be operated through a similar cycle for completing another call.

It may sometimes happen that an operator will wish to hold a connection and prevent a calling subscriber from releasing his line by hanging up his receiver, as, for example, when a fire or police call is given, or when a malicious call is given and it is desired to trace the connection to determine upon what line the call originated. In cases of this kind the operator depresses her key 160, which places a permanent ground upon the private conductor 104, extending from the cord circuit to the intermediate switch. This prevents the release of the intermediate switch and therefore holds a permanent ground upon private conductor 78. Thus a circuit is maintained through the winding 27 of relay 11, conductor 26, the winding 28 of relay 18, conductor 29, contacts 30 and 31 of relay 11 and contacts 32 and 61 of relay 18 to the private conductor 63 which is now grounded. The operation of the switch-hook at the calling subscriber's station therefore has no effect upon the line relays and the attendant may trace the call and determine the line which is connected with the particular cord circuit upon which the key 160 has been depressed.

Another feature of the line switch, which forms no part of my present invention, but which I will here explain, is the means by which the wipers 69, 70 and 71 are permitted to rotate continuously in one direction without having any normal position and without the danger of connecting the direct ground, which is associated with the private portion of the bank of this switch, with contacts of the other portions of the bank of this switch which may at the time of the rotation of the switch be in use in completing some other conversational circuit. It will be noted that the segment 64, which is the private segment, is of such length that it stands opposite two more contacts than either of the talking segments 57 or 58. It will also be noted that the first and last contacts which are opposite the private segment 64 are permanently grounded. When, in the rotation of the spider of this switch, the brush 71 arrives upon the last of the private contacts 247 or that which is permanently grounded, the brush 70 will be standing upon contact 245 which latter contact is entirely free from electrical connections. The next step of the spider places the wiper 71 upon the contact 246 which is likewise a free contact, and at the same time places the wiper 70 upon the first of the contacts of

the private bank which contact is also permanently grounded. In this way the current for maintaining the rotation of the spider can flow first from segment 64 through the brush 71 and contact 247 to ground then through segment 64, the brush 70 and contact 248 to ground without there being any possibility of a grounded brush coming in contact with either segment 57 or 58 and thus no disagreeable click will be given to subscribers who, for example, may be using either contacts 249 or 250 for conversational purposes at this time.

Another feature of this system is the means for indicating to an attendant at the central office when a line becomes accidentally grounded at some point either within or without the central office. In systems of this character heretofore, when the battery limb of the telephone line outside the exchange became accidentally grounded, the line selecting apparatus would be operated to select an idle trunk circuit and thus to extend the disordered line through circuits or apparatus not individual to the line. In this manner the trunk circuit would become tied up and useless and in case there were several lines disabled simultaneously it was possible to use up all of the available trunks with these disabled lines. By the present system when a ground occurs upon the line conductor 4 current flows from the main battery through conductor 14, coil 12 of line relay 13, contacts 10 and 9 of cut-off relay 11 and line conductor 4 to earth. This actuates relay 13 and closes a circuit from battery 14 through interrupter 42, the coil of motor-magnet 41, conductor 40, the now actuated contacts 39 and 38 of line relay 13, the closed contacts 37 and 31 of cut-off relay 11, contacts 32 and 33 of relay 18 and the now closed contacts 34 and 65 of relay 18 to ground. Thus the line switch 60 is maintained in its progressing condition independently of the grounds upon its private contacts and this switch will therefore continue to rotate until the attendant hearing the sound of the continuously moving switch either corrects the trouble on the line or interrupts the circuit by removing the fuses or otherwise. Likewise if the ground occurs on the other limb of the telephone line the line switch will rotate in this same manner when the receiver is removed from the hook by the subscriber who is attempting to make a call. The rotation will continue during the time the receiver is off the hook at the substation and the attendant will therefore have an opportunity of determining that there is trouble on this particular line without the subscriber having to go to some other telephone and call in to notify the attendant.

By having thus described my invention with respect to the accompanying illustration I do not wish to be understood to have

limited my invention to this particular embodiment, it being understood that many features of my invention are applicable to many other forms of specific apparatus. It is to be further understood that many changes may be made in the specific means of accomplishing the results herein set forth without departing from the spirit or scope of my invention.

10. What I claim is—

1. A telephone exchange system comprising a plurality of telephone lines, a plurality of link circuits, automatic switching means for completing the connection between a calling line and an idle link circuit, a call signal associated with the link circuit to indicate that a calling line has been automatically connected therewith and means permitting only two call signals being displayed before an operator simultaneously.

2. In a telephone system, the combination with a plurality of telephone lines, of a plurality of link circuits in charge of a single operator, automatic switching mechanism for establishing a connection between a calling line and an idle one of said link circuits, an indicator displayed when a calling line is connected with an idle link circuit, and means to prevent any other indicator being displayed in this particular operator's position when two of said indicators are simultaneously displayed.

3. In a telephone exchange system, the combination with a plurality of telephone lines, of a plurality of link circuits under the control of a single operator, switching mechanism for connecting a calling line with an idle link circuit, private conductors extending from the link circuits to the switching mechanism by which the idle or busy condition of the link circuit is automatically tested and means to cause all of the private conductors, extending to a particular operator's position, to test busy whenever two unanswered calls are simultaneously received at this operator's position.

4. In a telephone system, the combination with a plurality of telephone lines, of a plurality of link circuits at a single operator's position, automatic switching mechanism adapted to connect a calling line with an idle link circuit, a conductor for each link circuit over which the busy or idle condition of the link circuit is automatically tested by the automatic switching mechanism, the said link circuits for each operator's position being divided into two parts and means permitting only one unanswered call in each part simultaneously.

5. In a telephone exchange system, the combination with a telephone line, of an idle link circuit, automatic switching mechanism adapted to connect a calling line with

said link circuit, a normally open private conductor extending from the automatic switching mechanism to the link circuit, a pair of talking conductors extending from the calling line through the automatic switching mechanism to the link circuit, a source of current and a relay associated with the link circuit and adapted to be connected in a bridge of the talking strands and actuated over the calling telephone line, the actuation of said relay being adapted to connect the normally open private conductor with a pole of the main battery whereby the link circuit will thereafter test busy so that no other calling line will be connected with this link circuit during the conversation and a relay coil in circuit with said private conductor and energized over the said battery connection during conversation.

6. In a telephone exchange system, the combination with a plurality of telephone lines, of a plurality of link circuits at a single operator's position, automatic mechanism adapted to connect a calling line with an idle link circuit, normally open private conductors extending from the link circuits to the automatic switching mechanism, a central source of current, a relay associated with the answering end of said link circuit adapted to be actuated when a calling line is connected with the link circuit to establish the busy condition upon the private conductor extending to this link circuit and upon the private conductors extending to other link circuits at the same operator's position, a relay associated with the calling end of said link circuit and adapted to be actuated when a connection is established with a desired telephone line, the actuation of said relay being adapted to remove the busy condition from said other link circuits.

7. In a telephone system, the combination with a plurality of telephone lines, of a plurality of link circuits at a single operator's position, switching mechanism to connect a calling line with an idle link circuit, private conductors extending from the switching mechanism to said link circuits, a plurality of said conductors being normally connected together at the link circuit end, means whereby the establishment of a call on one of said link circuits places the busy condition upon the private conductor of that link circuit and upon the private conductors to which that private conductor was normally connected, and means whereby the establishment of a connection with a desired line removes the busy condition from the latter private conductors.

8. In a telephone system, the combination with a plurality of telephone lines, of a plurality of cord circuits, automatic switching mechanism to complete the connection between a calling line and an idle cord cir-

cuit, a private conductor for each cord circuit, said conductors being connected together at the cord circuit end and extending to the automatic switching mechanism, a 5 relay for the cord circuit actuated over the calling telephone line, a second relay for the cord circuit actuated over a local circuit when the calling end of the cord circuit is connected with a desired line, the actuation 10 of the first of said relays being adapted to ground all of said private conductors, the actuation of the second relay being adapted to remove the ground from all except one of said private conductors and to maintain a 15 ground upon the one private conductor so that the release of the first relay will not take the busy condition off of the one private conductor.

9. In a telephone system, the combination 20 with a plurality of telephone lines, of a plurality of link circuits at a single operator's position, automatic switching mechanism adapted to connect a calling line with an idle link circuit, a conductor for each link 25 circuit over which the busy or idle condition of the link circuit is automatically tested by the automatic switching mechanism, the said link circuits for each operator's position being divided into a plurality of parts and 30 means permitting only one unanswered call in each part simultaneously.

10. In a telephone system, the combination 35 with a plurality of telephone lines, of a plurality of link circuits in charge of a single operator, automatic switching mechanism for establishing a connection between a calling line and an idle one of said link 40 circuits, an indicator displayed when a calling line is connected with an idle link circuit and means to prevent any other indicator 45 from being displayed in this particular operator's position when a predetermined plurality of said indicators are simultaneously displayed.

45 11. In a telephone exchange system, the combination with a telephone line, of a cord circuit, line and intermediate switch circuits for establishing a connection between a calling line and said cord circuit, said intermediate switch having motion in two directions, a relay actuated over the line for completing the circuit of the motor-magnet for 50 operating the switch in one direction, a second relay actuated when the contacts of the switch come opposite a row having the contacts of an idle cord circuit therein to complete the circuit of the motor-magnet adapted to move the switch in the other direction, and a third relay adapted to be actuated 55 when the wipers of the intermediate switch arrive upon the contacts of an idle cord circuit.

60 12. In a telephone exchange system, the combination with a telephone line, of a cord circuit, line and intermediate switches for

establishing a connection between a calling line and said cord circuit, said intermediate switch having motion in two directions, a cut-off relay for the intermediate switch, a second relay actuated through normal contacts of said cut-off relay, the actuation of the second relay being adapted to complete the circuit of the motor-magnet for moving the contacts of the intermediate switch in one direction, a third relay actuated when the 70 contacts arrive opposite a row in which are the contacts of an idle cord circuit, the actuation of the third relay being adapted to complete the circuit of the motor-magnet for moving the switch in the other direction until its contacts arrive upon the contacts of an idle cord circuit, the actuation of the cut-off relay being adapted to interrupt the circuits of said second and third relays and to complete the talking circuit through the intermediate switch. 80

90 13. In a telephone exchange system, the combination with a telephone line, of a cord circuit, line and intermediate switches for establishing a connection between said line and said cord circuit, said intermediate switch having motion in two directions, a pair of motor-magnets, one for moving said switch in each direction, a source of interrupted current, a bank of contacts, a wiper sliding over said contacts when the 100 switch moves in one direction, one of said contacts corresponding to each row of cord circuit terminals with which the switch is adapted to connect, said contacts being adapted to have the busy condition placed 105 thereon whenever all of the cord circuits in the associated rows are busy, a relay adapted to close the circuit of said interrupted source and one of said motor-magnets through said wiper and said grounded contacts to cause the actuation of the motor-magnet until said wiper arrives upon a non-grounded contact, a second relay having its coil connected between said wiper and ground whereby its coil is shunted 110 when the wiper is on grounded contacts, the actuation of said second relay being adapted to complete the circuit of said interrupted source through the other motor-magnet to cause the intermediate switch to move 115 in the other direction to select the idle cord circuit. 120

14. In a telephone system, the combination with a telephone line, of a switch at the central office associated with said line, 125 a pair of relays normally connected, one in each limb of the telephone line and adapted to be simultaneously actuated to operate said line switch and select an idle trunk when the limbs of said line are closed at 130

the sub-station, the actuation of one of said relays alone, when a ground occurs upon a limb of the telephone line, being adapted to cause the continued rotation of said line switch without selecting an idle trunk.

15. In a telephone system, the combination with a telephone line, of a line switch for establishing an automatic connection, a plurality of trunk circuits upon one of which said line switch is normally standing, and means to cause the continued operation of said line switch without selecting a trunk when a ground occurs upon a limb of the telephone line.

16. In a telephone system, the combination with a telephone line, of a plurality of trunk circuits, a line switch for establishing the connection between said line and any one of said trunk circuits, a grounded central source of current, a pair of relays, one connected between each limb of said line and the opposite poles of said source, the actuation of both of said relays being adapted to cause the actuation of said line switch

to select an idle trunk, and the actuation of one of said relays only being adapted to cause the continued movement of said line switch without selecting an idle trunk.

17. In a telephone system, the combination with a telephone line, of a plurality of trunk circuits, a line switch for establishing the connection between said line and an idle one of said trunk circuits, a pair of relays actuated over the line when the limbs are connected together to cause the regular operation of said line switch, and means whereby a ground upon a limb of the telephone line will actuate only one of said relays to cause the actuation of said line switch without selecting an idle trunk.

Signed by me at Rochester, county of Monroe, and State of New York, in the presence of two witnesses.
